7 Claims. (Cl. 260—240)

This invention relates to a novel series of soluble 10 chemotherapeutic agents having substantial antiviral activity. More specifically these compounds are diphenylcarbonylmethinylhydrazidoalkyl quaternary salts.

The novel compounds of this invention have been found to have antiviral activity, either prophylactic or curative, against such viral infections as distemper virus, hepatitis virus (MHV₃), neurotropic virus (CLM), Coxsackie virus, Echo virus, hemadsorption virus, adenovirus, Newcastle disease virus, herpes simplex and, particularly, influenza virus (A or PR₈). The compounds are also very 20 water soluble thereby lending themselves readily to various routes of administration particularly subcutaneous routes or topical applications, for instance under the form of collyrium.

These compounds are represented by the following 25 basic structural formulas:

and

in which formulas X is a pharmaceutically acceptable anion such as chloride, iodide or bromide; Y is a quaternary ammonium radical of the group consisting of pyridinium

Preferred and advantageous compounds are those according to the following formulas

or

trialkylammonium

alkylpiperidinium

alkylpyrrolidinium

2

alkylmorpholinium

alkyl-N-alkylpiperazinium

15 and dialkyl-N-alkylpiperazinium

A represents a moiety of the group consisting of oxygen, sulfur, sulfonyl (SO₂), sulfinyl (SO), methylene, ethylene, vinylene (CH=CH) or a single valence bond; R and R₁ are hydrogen, halogen of atomic weight less than 80, alkoxy, methyl or hydroxy.

Preferably the substituents on the diphenylnucleus are in the para or 4-positions relative to the connection of the two phenyl rings.

(I)

30

45

or

65

70

in which A is oxygen, sulfur or a single bond and Y is trimethylammonium, pyridinium or morpholinium and X is as described above.

60 The compounds of this invention are prepared by condensing a diphenyl mono or bis glyoxal derivative with an alkanohydrazide ammonium halide having the following structure:

in which X and Y are as defined above for Formulas I and II. The starting material glyoxal can also be used in the form of an addition compound such as a hydrate, alcoholate for instance ethylate or methylate or a bisulfite addition product.

70 These glyoxal starting materials are all described in copending applications. An excess of the hydrazide of Formula V is usually employed. The

solvent is any unreactive organic solvent in which the reactants are mutually soluble. The lower alcohols, preferably, methanol, ethanol or isopropanol have been found to be very useful. Often a condensing acid such as acetic acid is advantageously present. Anhydrous conditions are particularly desirable. A reflux period of from 30 minutes to about three hours usually suffices for relatively complete reaction.

The products are isolated by cooling or by evaporation and trituration of the residue with ethyl ether. The desired quaternary products thereupon crystallize but because of their chemical and physical nature melting points cannot be obtained.

The term alkyl is used herein to define straight or branched saturated hydrocarbon residues of from 1 to 3 carbon atoms inclusive. Alkoxy groups are similarly comprised of 1 to 3 carbon atoms. The term "reactive halide" defines chloride, bromide or iodide anions. Of course other conventional nontoxic, pharmaceutically acceptable anions can be substituted therefor. Other modifications in the structures outlined are obvious to those skilled in the art such as other substituents in the benzene or heterocyclic portions of the chemical structures or using larger alkyl moieties however the essential features of the compounds of this invention are described hereabove and the methods of preparing representative compounds of this invention are described hereafter.

Example 1

A mixture of 2.26 g. of 4-phenoxyphenylglyoxal, 1.97 g. of acethydrazide pyridinium chloride, 5 ml. of glacial acetic acid and 25 ml. of absolute ethanol is heated at reflux for 30 minutes. The mixture is cooled and evaporated. The residue is triturated with anhydrous ethyl ether to obtain a white crystalline product,

[(4-phenoxyphenylcarbonyl)methinylhydrazidomethyl] pyridinium chloride.

Example 2

A mixture of 2.2 g. of 4-glyoxyldiphenylmethane hydrate, 2.45 g. of acethydrazide pyridinium chloride, 5 ml. of glacial acetic acid and 25 ml. of absolute methanol are heated at reflux for 3 hours. Cooling separates the desired product, [(4-benzylphenylcarbonyl)methinylhydrazidomethyl] pyridinium chloride.

Example 3

A mixture of 1 g. of diphenylethane-4-glyoxal, 1 g. of acethydrazide pyridinium chloride, 2.5 ml. of acetic acid and 15 ml. of ethanol is heated at reflux for 3 hours, cooled and concentrated. The residue is triturated with ether to give [(4-phenethylphenylcarbonyl)methinylhydrazidomethyl] pyridinium chloride.

Example 4

A mixture of 2.98 g. of 4,4'-bisglyoxylyldiphenylethane, 5.4 g. of acethydrazide pyridinium bromide, 5 ml. of acetic acid and 25 ml. of methanol is heated at reflux for 3 hours. Cooling gives diphenylethane-4,4'-bis(carbonylmethinylhydrazidomethylpyridinium bromide).

Example 5

A mixture of 3.18 g. of 4,4'-bisglyoxylyldiphenylether, 5.4 g. of acethydrazide pyridinium chloride, 5 ml. of acetic acid and 50 ml. of ethanol is heated at reflux for 3 hours, then cooled and concentrated. Trituration with ether gives diphenylether-4,4'-bis(carbonylmethinylhydrazidomethylpyridinium chloride).

Example 6

A mixture of 2.56 g. of diphenyl-4-glyoxal ethylate, 3 g. of acethydrazide pyridinium chloride, 5 ml. of acetic acid and 25 ml. of ethanol is heated at reflux for 30 minutes, then cooled. The mixture is evaporated to dryness in vacuo to give, upon trituration with ether, [(4-bi-

phenylcarbonyl)methinyl-hydrazidomethyl] pyridinium chloride.

Example 7

5 A mixture of 3.02 g. of 4,4'-bisglyoxylylbiphenyl hydrate, 6 g. of acethydrazide pyridinium chloride, 5 ml. of acetic acid and 50 ml. of ethanol is heated at reflux for 30 minutes, cooled and concentrated. Trituration of the residue gives a crystalline precipitate, biphenyl-4,4'-bis(carbonylmethinylhydrazidomethylpyridinium chloride).

Example 8

15 A mixture of 2.46 g. of biphenyl-4-glyoxal hydrate, 2.9 g. of acethydrazide methylmorpholinium iodide, 5 ml. of acetic acid and 25 ml. of methanol is heated at reflux for 2 hours. The cooled mixture is concentrated and cooled to give the desired [(4-biphenylcarbonyl)methinylhydrazidomethyl]methylmorpholinium iodide.

Example 9

20 A mixture of 2.3 g. of 4-phenylthiophenylglyoxal, 2.1 g. of acethydrazide trimethylammonium chloride, 7 ml. of acetic acid and 30 ml. of ethanol is heated at reflux for 4 hours, then worked up as above to give [(4-phenylthiophenylcarbonyl)methinylhydrazidomethyl] trimethylammonium chloride.

Example 10

25 A mixture of 2.4 g. of 4,4'-bis-glyoxylystilbene hydrate, 5.1 g. of acethydrazide triethylammonium bromide, 5 ml. of acetic acid and 40 ml. of ethanol is reacted and worked up as in Example 3 to give stilbene-4,4'-bis-carbonylmethinylhydrazidomethyltriethylammonium bromide).

Example 11

30 A mixture of 3.3 g. of 4,4'-bisglyoxylyldiphenylsulfoxide ethylate, 5.8 g. of α -ethylacetohydrazide methylpiperidinium bromide, prepared by quaternizing the hydrazide of Petrie and Horsley (U.S. Pat. No. 2,834,781), 10 ml. of acetic acid and 50 ml. of isopropanol is heated at reflux for 5 hours. Cooling, evaporation and trituration with ether gives the desired diphenylsulfoxide-4,4'-bis(carbonylmethinylhydrazidoisopropyl methylpiperidinium bromide).

Example 12

35 A mixture of 1.5 g. of 2-phenoxyphenylglyoxal hydrate, 1.8 g. of acethydrazide trimethylammonium chloride, 5 ml. of acetic acid and 25 ml. of ethanol is heated at reflux for 2 hours and worked up as in Example 1 to give [(2-phenoxyphenylcarbonyl)methinylhydrazidomethyl] trimethylammonium chloride.

Example 13

40 A mixture of 1.2 g. of 4-phenylsulfonylphenylglyoxal, 1 g. of propionylhydrazide methylpyrrolidinium chloride, prepared by quaternizing the hydrazide of Petrie, 5 ml. of acetic acid and 25 ml. of methanol is heated at reflux for several hours. Working up as described above gives [(4-phenyl-sulfonylphenylcarbonyl)methinylhydrazidoethyl] methylpyrrolidinium chloride.

Example 14

45 A mixture of 2.5 g. of biphenyl-4-glyoxal, 2.8 g. of acethydrazide N-methylpiperazinium dimethochloride, prepared as in Petrie, 10 ml. of acetic acid and 50 ml. of ethanol is heated at reflux for 4 hours, cooled and evaporated. Trituration with ether gives the desired diquaternary salt.

Example 15

50 A mixture of 2.7 g. of 4-phenoxyphenylglyoxal, 2.5 g. of acethydrazide methyl-N-methylpiperazinium chloride, 10 ml. of acetic acid and 40 ml. of isopropanol is heated at reflux for 2 hours, cooled and evaporated. Trituration with ether gives [(4-phenoxyphenylcarbonyl)

methinylidrazidomethyl] 1,4-dimethylpiperazinium chloride.

Example 16

A mixture of 2.8 g. of 4'-methoxybiphenyl-4-glyoxal, 2.5 g. of acethydrazide pyridinium chloride, 10 ml. of acetic acid and 75 ml. of methanol is heated at reflux for 30 minutes and worked up as in Example 1 to give [(4'-methoxy-4-biphenylcarbonyl)methinylhydrazidomethyl] pyridinium chloride.

Example 17

A mixture of 1.5 g. of 3'-chloro-4'-methoxybiphenyl-4-glyoxal ethylate, 1.8 g. of acethydrazide trimethylammonium bromide and 100 ml. of isopropanol is heated at reflux for 6 hours. Working up as described above gives [(3'-chloro-4'-methoxy-4-biphenylcarbonyl)methinylhydrazidomethyl] trimethylammonium bromide.

Example 18

Repeating Example 15 but using 1.2 g. of 4'-fluoro biphenyl-4-glyoxal gives the 4'-fluoro analogue; using 1.4 g. of the 4'-bromobiphenyl-4-glyoxal gives the 4'-bromo analogue; using 1.1 g. of the 4'-methylbiphenyl-4-glyoxal gives the 4'-methyl quaternary.

Example 19

A mixture of 0.9 g. of 4'-hydroxybiphenyl-4-glyoxal hydrate, 1 g. of acethydrazide pyridinium chloride, 5 ml. of acetic acid and 20 ml. of ethanol is heated at reflux for 1 hour to give the desired 4'-hydroxy-pyridinium chloride. Substituting the 4'-n-propoxyglyoxal gives the corresponding 4'-n-propoxy-pyridinium chloride.

Example 20

A mixture of 1.1 g. of 3,3'-bisglyoxylylbiphenyl is reacted with 2.2 g. of acethydrazide pyridinium chloride as described in Example 7 to give the 3,3'-isomer.

Example 21

A mixture of 1.6 g. of 4-(4'-chlorophenoxy)phenylglyoxal hydrate, 1.8 g. of acethydrazide triethylammonium chloride and 40 ml. of methanol is heated at reflux for 4 hours. Cooling, concentration and trituration gives the desired [(4'-chloro-4-phenoxyphenylcarbonyl)methinylhydrazidomethyl] triethylammonium chloride.

What is claimed is:

1. A quaternary salt selected from the group consisting of compounds of the formulae:

and

in which alkyl is of from 1 to 3 carbon atoms; X is a reactive halide; Y is a quaternary ammonium radical selected from the group consisting of pyridinium, trialkylammonium, alkylpiperidinium, alkylpyrrolidinium, alkylmorpholinium, alkyl-N-alkylpiperazinium and dialkyl-N-alkylpiperazinium, each of said alkyl moieties is of from 1 to 3 carbon atoms; A represents a member selected from the group consisting of oxygen, sulfur, sulfonyl, sulfinyl, methylene, ethylene, vinylene and a direct link; R is a member selected from the group consisting of hydrogen, alkoxy of from 1 to 3 carbon atoms, methyl, chloro and hydroxy; and R1 is a member selected from the group consisting of hydrogen and chloro.

2. A chemical compound of the formula:

in which X is a reactive halide.

3. [(4-phenoxyphenylcarbonyl)methinylhydrazidomethyl] pyridinium chloride.

4. Diphenylether - 4,4' - bis(carbonylmethinylhydrazidomethyl) pyridinium chloride.

5. Biphenyl - 4,4' - bis(carbonylmethinylhydrazidomethyl) pyridinium chloride.

6. [(3'-chloro-4'-methoxybiphenylcarbonyl)methinylhydrazidomethyl] trimethylammonium bromide.

7. [(4-biphenylcarbonyl)methinylhydrazidomethyl] methylmorpholinium chloride.
